PISTON PACKING

William Edward O'Shei, London, England

Application October 25, 1949, Serial No. 123,368
In Great Britain June 30, 1948

21 Claims. (Cl. 121—97)

1

The present invention relates to fluid pressure motors of the oscillating paddle type as described for example in British specifications Nos. 237,455 and 546,483. Such motors are generally designed for operation by suction and are used extensively for driving the windscreen wiper on a vehicle. More particularly, the invention relates to the construction of the paddle and to a method of assembling the paddle in the paddle chamber of the motor.

Such paddles have hitherto been constructed of two cupped packing members made of leather and of generally rectangular shape, the two cupped leather members being assembled with their flanges facing one another and spaced by a pair of flanged inner metal plates which embrace the transverse shaft about which the paddle rocks, two further metal plates being fitted outside the cupped leathers and the whole assembly being secured together by transverse rivets. This construction is illustrated in British specifications Nos. 237,455 and 444,452.

The paddle leathers are greased when the motor is assembled but after a time leathers become hardened. This hardening of the leathers appears to be due to moisture getting into the paddle chamber and forming an emulsion with the lubricant. Moisture gets into the paddle chamber by reason of the fact that the motor, when used for driving a windscreen wiper, is in use during rainy and damp weather as result of which damp air is sucked into the motor, and in some cases rain on the driving shaft may also be sucked into the motor through the shaft bearing. Since windscreen wiper motors remain out of use for long periods of time, particularly during spells of dry weather, the cupped leathers harden with a permanent "set" corresponding with the dimensions of that part of the paddle chamber in which the paddle rests in its "parked" position. As a result the paddle will not flex to conform with the surface of the paddle chamber when the paddle moves into another part of the chamber, for example when the motor is operating, as a result of which air leakage takes place around the leathers with consequent loss of power of the motor. To overcome this difficulty, spring expanders are generally fitted inside the flanges of the cupped leathers as described for example in British specification No. 306,381, with the object of expanding the flanges into close contact with the wall of the piston chamber, but this has not proved a complete solution of the problem. Moreover, the provision of expanders increases the friction between the cupped leathers and the wall

2

of the paddle chamber which reduces the power of the motor and necessitates a higher minimum vacuum before the motor operates. This is a disadvantage with suction operated windscreen wiper motors since the available suction on a vehicle is limited.

As previously mentioned, the packing members are preformed to their cupper shape before assembly with the other components of the paddle 10 and before assembly of the paddle unit within the paddle chamber. This necessitates careful forming of the paddle leathers to avoid the formation of wrinkles around the flanges, particularly at the curved corner portion thereof, and to ensure that they will closely conform to the internal shape of the paddle chamber of the motor. In assembling the paddle unit in the paddle chamber, the paddle is swung from one to the other of its limiting positions to make sure that the leathers are properly assembled. A dummy top cover, which is open to permit inspection, is fitted before the proper cover is fitted, and any part of the paddle which becomes nipped between the dummy cover and the top edge of the paddle 15 chamber is carefully trimmed off before the proper cover is fitted. The fitting of the paddle unit thus necessitates employing a skilled and properly trained operator.

The present invention has for its object to provide an improved paddle, and an improved method of assembling the paddle within the paddle chamber which permits employing less skilled operators than has hitherto been necessary. To this end, from one aspect, the invention consists in a 20 fluid pressure motor of the oscillating paddle type, in which the cupped packing members are made of rubber-like material, and wherein members of plates of metal or other substantially rigid material, are secured over the outer surfaces of the packing members, said members or plates being of such a size that the clearance between the periphery of an outer member or plate and the wall of the paddle chamber is insufficient to permit the flange to be sucked or otherwise moved 25 so that it, or a part thereof, can face in the opposite direction to that in which it is designed to operate. Since it is desirable to lubricate the paddle with grease, the material from which the packing members are made preferably possesses oil-resistant properties so that it does not become perished by the lubricant. Preferred materials for the packing members are polyvinyl chloride, neoprene, or the material known under the registered trade-mark "Buna." Such materials are furthermore lubricated by water, so that the 30 35 40 45 50 55

moisture entering the paddle chamber assists in lubricating the paddle packings without hardening them.

By making the packing members of such materials, the elastic properties thereof enable the same to distort and flex to conform with the inner surface of the paddle chamber without the formation of wrinkles. Furthermore, the increased flexibility of the flanges of the packing members enables the suction to hold the flanges in close and substantially leakproof contact with the wall of the paddle chamber without the necessity of spring expanders. Thus the invention not only reduces leakage past the paddle but also reduces the friction between it and the paddle chamber, and thus provides a motor which is able to operate on lower degrees of vacuum than has hitherto been possible.

Due to the highly flexible nature of the material from which the packing members are made, there is a tendency for the suction to pull upon the cupped flanges and pull the packings "inside-out," that is to say to pull the flanges from their desired inwardly facing direction so that they face in the reverse direction. The rubbing of the edge of the flange on the wall of the paddle chamber also produces a similar tendency. To avoid this undesirable reversal of the packings, outer members or plates of metal or other substantially rigid material are secured over the outer surfaces of the packing members, said plates being of such a size that the clearance between the periphery of an outer plate and the wall of the paddle chamber is insufficient to permit the flange to be sucked or otherwise moved so that it, or a part thereof, can face in the opposite direction to that in which it is designed to operate. The clearance between the periphery of an outer plate and the wall of the chamber may be such that it does not substantially exceed, and is preferably less than, the thickness of the material of the flange of the adjacent packing member at all points around said periphery, although it will be obvious that small portions of the periphery may be cut away or notched provided that the gap thus formed is not large enough to permit the adjacent part of the flange to be turned inside out under the operating conditions of the motor. The plate members may, of course, be apertured or perforated at their inner regions.

The packing members may be preformed, for example by moulding, to a cupped shape. Preferably, however, the packing members are initially made flat, for example by being cut from sheet material, with a size which is greater than the cross-section of the paddle chamber of the motor, the peripheral zones of the packing members being folded over to form the cupped flanges by inserting the packings into the paddle chamber after they have been assembled into the paddle unit. In this way the packings conform to the actual contour of the paddle chamber, and due to the elastic nature of the material from which the packings are made, the material compresses around the curved corners of the flanges and the production of wrinkles does not take place. Furthermore, with this construction, the elastic bias on the flanges of the packings serves to urge them firmly and evenly into contact with the wall of the paddle chamber without the provision of spring expanders, although expanders may be provided if desired.

A feature of the invention therefore consists in a paddle for fluid pressure motors of which the

packing members are cut from sheet material possessing elastic properties similar to rubber and assembled in the paddle unit without being preformed to the cupped form which the packing members will finally assume when the paddle unit is assembled in the motor. Preferably the packing members are cut from sheet polyvinyl chloride, synthetic rubber, or the like of a thickness, for example of $\frac{1}{2}$ ".

According to another feature of the invention, the two packing members are joined together at the top end of the paddle, in order that the maximum arc of movement of the paddle may be obtained without risk of the cupped flanges at the top end of the paddle being sucked out of the auxiliary arcuate chamber when the paddle is in either of its extreme limiting positions.

According to a further feature of the invention, the paddle packing members, or at least those portions of the surfaces thereof which wipe against the walls of the paddle chamber, are unpolished or roughened, in order to provide small cavities for retaining oil and grease and distributing it over the walls of the paddle chamber. This surface roughening may be produced by moulding or calendering the rubber-like material on linen or similar material having a rough surface.

From another aspect, the invention consists in an improved and novel method of assembling the paddle in a fluid motor without preforming the packing members to a cupped shape, and in forming the cupped flanges to the packing members during the actual assembling of the paddle unit in the paddle chamber.

A further feature of the invention consists in constructing the spacer member between the two paddle packings as a single unit, preferably as a die-casting, into which the motor shaft is fitted. Preferably the die-casting is formed integrally with outwardly extending projections which are adapted to pass through apertures in the packing members and outer plates and to be finally spun or riveted over or fitted with nuts to secure the packing members and outer plates to the inner unit. With this construction there are no apertures which extend from one side of the paddle assembly to the other through which rivets pass so that leakage from one side to the other through such apertures is completely avoided.

In order that the invention may be more clearly understood, reference will now be made to the accompanying drawings, in which—

Fig. 1 is a perspective view of the paddle before being fitted in the motor housing.

Fig. 2 is a section through the motor housing with the paddle in position.

Fig. 3 is a scrap view showing the paddle being inserted into the motor housing.

Fig. 4 is an end view of Fig. 3.

Fig. 5 shows a section through the paddle during assembly of the components thereof.

Referring to the drawings, the paddle comprises a central spacer 3 constructed as a die-casting, such as a zinc-base die-casting, cast integrally with two projections 4 extending from each side. One of these projections 4' is made longer than the other three. The two packing members 1, 1' of sheet polyvinyl chloride or like material are fitted to opposite sides of the central member, being formed with apertures which fit over the projections 4. Outer metal plates 2, 2' are then assembled over the outer surfaces of the packing members, these outer plates also be-

ing provided with apertures to fit over the projections 4. A cross-section of the paddle as so far assembled is shown in Figure 5.

The components of the paddle are then secured together and the packing members 1, 1' clamped between the outer plates 2, 2' and the central member 3 by spinning or riveting over the ends of the projections 4. Before the longer projection 4' is riveted over, a valve member 17, also constructed of polyvinyl chloride or like material and shaped as shown in Figure 4, is fitted over the projection 4' between two metal washers 19 and 20. The end of the projection 4' is then riveted over to hold these washers and the valve member 17 in position on the paddle assembly. The central member 3 is cored with apertures into which the motor shaft 5 and the valve shaft 5', carrying the valve operating member 20, are respectively fitted, for example by a force fit. These shafts may be formed at their ends which fit into cored apertures with longitudinal grooves or splines in order positively to interlock the shafts with the casting.

The packing members are made larger than the cross-section of the paddle chamber 6 of the motor by an amount approximately equal to the width of the flanges to be formed around each packing member, and the outer metal plates 2, 2' of the paddle assembly are made of such a size that they will clear the inner walls of the paddle chamber 6 by an amount less than the thickness of the sheet material from which the packing members 1, 1' are made. The plates 2, 2' are preferably formed inwardly at 7, the central member 3 being similarly shaped, so that the thickness of the paddle unit can be made as small as possible to permit the maximum arc of swing to be obtained. If desired, the plates 2, 2' may also be provided with small notches 16 in their peripheries in order to clear the curved corners of the auxiliary arcuate chamber 14 and thus still further increase the maximum arc of swing.

The top and bottom ends of the outer plates 2 and 2' are also bent inwardly in order to cause the top and bottom ends of the packing members to be inclined slightly inwards as shown, for example by 8 in Fig. 3. Preferably, however, the top ends of the two packing members are joined together. This may be most easily effected by cutting the two packing members as an integral unit from the sheet material, the two members being joined at 9.

To assemble the complete paddle unit in the motor, the unit is just entered into the paddle chamber 6 with the peripheral zones of the packing members bent inwardly towards one another. The disposition of the peripheral zones of the packing members in this way is facilitated by the curved forms of the half bearings 10 in the top edges of the casting forming the paddle chamber 6, in which the paddle shaft will finally rest. The paddle unit is then pushed vertically downwards into the casting, during which the movement of the side peripheral zones of the packing members are each progressively folded over inwards, as shown in Figs. 3 and 4. Until the paddle unit almost reaches the bottom of the paddle chamber, the bottom peripheral zones of the packing members remain unfolded, but when these bottom zones touch the bottom of the chamber 6, continued downward movement of the paddle unit causes these bottom zones to fold over inwardly and assume the positions shown in Fig. 2. This folding over of the bottom zones is assisted by the

arcuate form of the bottom of the paddle chamber 6 and also by the fact that the bottom zones are biased inwardly by the ends of the outer plates 2, 2'. Due to the elastic properties of the packing members, the curved portions of the flanges between the side and bottom zones are formed without the production of wrinkles which would cause leakage past the packing.

The insertion of the paddle unit into the paddle chamber as above described is facilitated by the application of grease to the paddle. This may be conveniently applied to the space between the peripheral zones of the two packing members.

After the simple assembly operation above described has been completed and the paddle shaft is fitted and resting in its half bearings 10 at the top edge of the paddle chamber, and the extension bearing 11 is resting in the corresponding recess 12 in the casting in known manner, it is only necessary to fit the top cover 13 of the motor which incorporates the auxiliary arcuate chamber 14 for accommodating the top end of the paddle. The fitting of the top cover automatically folds in the top portions of the sides of the packing members. If the two packing members are separate (instead of being joined together at their top ends as shown) these top edges will be folded inwards upon engaging the arcuate surface of the auxiliary chamber 14 (assisted by the fact that these edges are already inwardly inclined by the shape of the top ends of the outer plates 2, 2') with a smooth surface to the curved corner portions of the flanges. The cover is then secured in position by means of screws 15.

As above described, the paddle also carries the valve 17 which serves to seal off the motor chamber, by engaging with the seating 18, when the paddle is in the "parked" position.

The feature of joining the paddle packing members together at their top ends as above described can be used with advantage whether the packing members are made from synthetic rubber, leather or other material. In paddle type motors as hitherto constructed, leakage past the packing at the top end of the paddle is likely, particularly under the conditions obtaining upon reversal of the paddle movement at each end of its stroke. It has been found that when the paddle is at either of its extreme limiting positions, there is a tendency for the portion of the paddle packing working in the auxiliary chamber to be pulled out of the auxiliary chamber by the applied suction. When the paddle reaches the end of its stroke in one direction, the flange of the top end portion of the packing member which in that position is adjacent the main chamber usually partially protrudes into the main chamber owing to the thickness of the paddle. Thus when the suction is applied to this side of the paddle to move it in the opposite direction, this protruding portion of the flange is subjected to the suction which tends to draw it out of the auxiliary chamber and cause leakage of air past the flange, and also tends, upon movement in said opposite direction, to fold back the flange so that the top edge of the packing may become wrinkled or damaged as it is moved into the auxiliary chamber by the effect of the suction on the main body of the paddle in the main chamber. For this reason, the maximum arc of movement of the paddle had to be limited so that this top flange will not fold back upon reversal.

By joining the two top flanges together, the possibility of the flanges reversing their directions is avoided. The paddle packings may be formed in one piece as above described or in two or more parts which are subsequently joined together.

The method of constructing the central member 3 of the paddle assembly as a single die-casting also presents advantages even if the packing members are made, as hitherto, of leather. Previously the spacing member has generally been constructed of two metal plates, sometimes provided with flanges around their edges as described for example in British specifications Nos. 237,455 and 444,452; the components of the paddle assembly being secured together by rivets which pass through the outer plates, the packing member, the inner plates and also through an aperture in the transverse shaft about which the paddle rocks. In order that the motor may operate on the lowest possible degree of suction, it is important that leakage from one side of the paddle to the other should be reduced as much as possible and also that the paddle should move with the minimum friction within the paddle chamber. The method of constructing the paddle as hitherto employed possesses such difficulties in manufacture by mass production methods that these desiderata cannot be uniformly obtained. Thus, for example, since the rivets securing the paddle assembly together pass through apertures which extend from one side of the paddle to the other, a leak often occurs through this aperture which reduces the efficiency of the motor. If the rivets are very tightly sealed over to reduce this leakage, it often occurs that the two inner metal members and the packing members located thereby become forced out of alignment as a result of which the packing members may bear unevenly on the walls of the paddle chamber, thereby increasing the friction and also giving rise to the possibility of leakage around the packing member. Furthermore, if the assembly is thus tightly riveted, unless very great care is taken to ensure that the transverse shaft about which the paddle rocks is exactly at right angles to the longitudinal axis of the paddle, then again the paddle packing will bear more heavily against one wall of the paddle chamber than the other, again with increase of friction and risk of leakage.

By reason of constructing the central member as a solid unitary member according to this invention, any rivet passed therethrough for assembling the outer plates and the packing members to the central unit may be tightly riveted without any possibility of causing misalignment as with the previous constructions. Preferably, however, rivets which pass from one side to the other of the paddle are completely eliminated and the rivets are formed by the integrally cast projections, as above described, so that leakage from one side of the paddle to the other by reason of rivet apertures is completely avoided.

Furthermore since the driving shaft is fitted into an aperture or recess in the central unit, which aperture or recess can be accurately formed in the unit, for example during the die-casting operation, the shaft is accurately positioned with respect to the paddle even when made in commercial mass production.

By die-casting the central unit, it can be easily

shaped and waisted to permit the paddle to execute an increased arc of movement. The arc of movement of a motor of the type to which this invention relates is generally restricted by the 5 paddle engaging with the edges of the auxiliary arcuate chamber, and by means of this novel construction the inner unit can be shaped and waisted to increase its arc of movement, the short end of the inner unit being curved inwardly to 10 avoid the packing members from moving out of the auxiliary arcuate chamber when the paddle reaches the extreme limit of its increased arc of movement. By means of this construction an arc of movement of about 140° can be obtained compared with the usual arc of 126°.

The shaft 5' carrying the valve operating member 20 may be accurately located in the die-cast central unit 3. If desired, the shaft 5' and the valve operating member 20 carried thereby may be 20 die-cast integrally with the inner unit. The valve operating member 20 has faces for actuating the valve by an over-centre action when it reaches the limit of its stroke (the construction of the valve mechanism is well-known in the art) 25 and since the invention enables the valve operating member to be accurately located with respect to the paddle, accurate timing between the valve and the movement of the paddle may be obtained by commercial manufacturing methods, 30 this timing being particularly important where the paddle executes an increased arc of movement as above described.

Whilst a particular embodiment of the invention has been described, it will be understood that 35 various modifications may be made without departing from the scope of the invention. Thus if it be desired to reduce the weight of the inner unit, it may be cored out to form cavities such as indicated at 3', which cavities may, if desired, 40 be used as a reservoir or reservoirs for grease or other lubricant, grooves or apertures being provided in the casting connecting the reservoir cavity or cavities with the peripheral edges of the casting.

45 Moreover, the motor shaft need not be inserted into an aperture in the central member as described but can be connected to the paddle in a floating manner, for example by constructing the motor shaft as a bent shaft which fits into an 50 appropriately shaped aperture or cavity formed in the die-casting. For example, an L-shaped cavity may be formed in the die casting to receive the bent motor shaft which is held in position by securing the packing members and outer plates 55 in position.

I claim:

1. A fluid pressure motor of the oscillating paddle type comprising a paddle chamber and a paddle movable in said chamber, said paddle comprising a spacer having a pair of cupped packing members made of rubber-like material positioned on opposite sides of said spacer with their cuped edges facing towards one-another, and a pair of substantially rigid outer members secured 65 respectively over the outer surfaces of the packing members, said outer members being of such a size that the clearance between the periphery of an outer member and the wall of the paddle chamber is insufficient to permit the flange to be sucked or otherwise moved so that it, or a part thereof, can face in the opposite direction to that in which it is designed to operate.

2. A fluid pressure motor of the oscillating paddle type comprising a paddle chamber and a paddle movable in said chamber, said paddle com-

prising a spacer having a pair of cupped packing members made of rubber-like material positioned on opposite sides of said spacer with their cupped edges facing towards one another, and a pair of substantially rigid outer members secured respectively over the outer surfaces of the packing members, said outer members being of such a size that the clearance between the periphery of an outer member and the wall of the paddle chamber is not greater than the thickness of the material of the flange of the adjacent packing member at all points around said periphery, except for any small portions of said periphery which may be cut away and are sufficiently small to prevent the adjacent part of the flange from being turned inside out under the operating conditions of the motor, and except at any parts of said periphery where the flanges of the two packing members are joined together.

3. Device as claimed in claim 2, in which the 20 packing members are cut from sheet material of a size larger than the cross-section of the paddle chamber, the edges of the packing members being folded over to form the flanges by the operation of inserting the paddle into the paddle chamber.

4. A paddle for fluid pressure motors of the oscillating paddle type, comprising a spacer, a pair of packing members cut from sheet rubber-like material and assembled one on either side of the spacer, a rigid plate member positioned over the outer surface of each packing member, and means for securing the outer members to the spacer with the packing members secured therebetween.

5. Device as claimed in claim 4, wherein the 35 two packing members are formed integrally from sheet material, being joined together at the region which forms the top end of the paddle.

6. Device as claimed in claim 5, wherein at least the bottom ends of each plate member are 40 bent inwardly to incline the bottom ends of the packing members inwardly.

7. A paddle as claimed in claim 6, wherein the top ends of the metal plates are also bent inwardly.

8. Method of assembling a paddle in a fluid motor of the oscillating paddle type, which consists in constructing the paddle with packing members cut from sheet rubber-like material and of larger size than the cross-section of the paddle chamber, and folding the edges of the packing member inwardly by the operation of inserting the paddle into the paddle chamber.

9. Method of assembling the paddle unit of a fluid pressure motor in the paddle chamber, which consists in positioning the paddle, having unflanged packing members of rubber-like material, above the half bearings of the paddle chamber and entering the paddle into the chamber with the peripheral side zones of the packing members bent inwardly towards one another, and advancing the paddle into the chamber to complete the folding over of the side zones and the bottom peripheral zones of the packing members.

10. A paddle for a fluid pressure motor of the oscillating paddle type, comprising a central die-casting, at least one projection extending from opposite faces of said die-casting and formed integrally therewith, a packing member positioned over each face of the die-casting with the projections passing through apertures therein, a rigid plate member positioned over the outer surfaces of said packing members with the projections passing through apertures therein, and

means on the free ends of said projections for securing the packing members and plate members to the central diecasting.

5 11. A paddle as claimed in claim 10, wherein at least the bottom ends of the plate members are inclined inwardly towards the central die-casting.

12. A paddle for a fluid pressure motor of the oscillating paddle type, comprising a central member, at least one projection extending from opposite faces of said central member, a packing member positioned over each face of the central member with the projections passing through apertures therein, a rigid member, positioned over the outer surfaces of said packing members with the projections passing through apertures therein, and means on the free ends of said projections for securing the packing members and rigid members to the central member.

13. A paddle as claimed in claim 12, wherein the two packing members have their top edges joined together.

14. A paddle as claimed in claim 13, wherein the two packing members are formed integrally and applied to the central member by folding about the top end of the central member.

15. A fluid pressure motor of the oscillating paddle type, comprising a paddle chamber, a paddle, movable in said chamber and comprising a central diecasting, at least one projection extending from opposite faces of said diecasting and formed integrally therewith, a packing member made of rubber-like material positioned over each of the diecasting with the projections passing through apertures therein, a rigid plate member positioned over the outer surfaces of said packing members with the projections passing through apertures therein, and means on the free ends of said projections for securing the packing members and plate members to the central diecasting, said plates being of such a size that the clearance between the periphery of an outer plate and the wall of the paddle chamber is insufficient to permit the flange to be sucked or otherwise moved so that it or a part thereof can face in the opposite direction to that in which it is designed to operate.

16. A fluid pressure motor as claimed in claim 15, in which the packing members on opposite sides of the paddle are joined together at least at the top of the paddle.

17. For a fluid pressure motor of the oscillating paddle type a paddle comprising a spacer having a rocker shaft extending from the side thereof at a point between the top and bottom ends of the spacer but closer to its top end than to its bottom end, two cupped packing members disposed respectively on opposite surfaces of said spacer with their cupped edges extending around the entire periphery of the spacer and facing towards one another, and means joining said packing members together at the top of the paddle, said packing members otherwise having their edges separated around substantially their entire peripheries.

18. For a fluid pressure motor of the oscillating paddle type, a paddle comprising a spacer having a rocker shaft extending from the side thereof at a point between the top and bottom ends of the spacer but closer to its top end than to its bottom end, packing members positioned on opposite surfaces of said spacer, said packings being made from a single piece of rubber-like material which is of a width greater than the width of the spacer and of a length greater than twice the length of

11

the spacer and which is folded around the top of the spacer and outer plates positioned against the outer surfaces of the packing members and secured to the spacer.

19. A fluid pressure motor of the oscillating paddle type comprising a motor housing having a main arcuate paddle chamber, a paddle having a rocker shaft extending from the side thereof at a point between the top and bottom ends of the paddle but closer to its top end than to its bottom end, said paddle being positioned within the housing with said rocker shaft movable in a bearing carried by the housing coaxial with the centre of curvature of the main arcuate chamber, said housing also being formed with an auxiliary arcuate chamber concentric with the main arcuate chamber within which the top end of the paddle moves whilst the bottom end of the paddle moves in the main arcuate chamber, said paddle comprising a spacer from which the rocker shaft projects, and cupped packing members positioned on opposite sides of said spacer with their cupped edges facing towards one another, said packings being cut from a single sheet of rubber-like material which is folded around the top end of the spacer and secured in position on opposite sides of the spacer.

20. A fluid pressure motor as claimed in claim 19, wherein the paddle packings are cut from sheet rubber-like material.

21. A fluid pressure motor of the oscillating paddle type comprising a motor housing having a main arcuate paddle chamber, a paddle having a rocker shaft extending from the side thereof at a point between the top and bottom ends of the

12

paddle but closer to its top end than to its bottom end, said paddle being positioned within the housing with said rocker shaft movable in a bearing carried by the housing coaxial with the centre of curvature of the main arcuate chamber, said housing also being formed with an auxiliary arcuate chamber concentric with the main arcuate chamber within which the top end of the paddle moves whilst the bottom end of the paddle moves in the main arcuate chamber, said paddle comprising a spacer from which the rocker shaft projects, cupped packing members positioned on opposite sides of said spacer with their cupped edges facing towards one another, and means for joining flanges of said packings together at the top of the paddle.
